UNITED STATES PATENT OFFICE.

JOHN W. LIPPINCOTT, OF LITTLE ROCK, ARKANSAS, ASSIGNOR OF ONE-HALF TO CARRIE A. LIPPINCOTT, OF LITTLE ROCK, ARKANSAS.

PARTITIONING AND STABILIZING APPLIANCE.

1,270,532.

Specification of Letters Patent. Patented June 25, 1918.

Application filed December 8, 1917. Serial No. 205,231.

To all whom it may concern:

Be it known that I, JOHN W. LIPPINCOTT, a citizen of the United States, residing at Little Rock, in the county of Pulaski and State of Arkansas, have invented certain new and useful Improvements in Partitioning and Stabilizing Appliances of which the following is a specification.

My invention relates to means for preventing the shifting of goods, merchandise, wares, etc., while in freight cars, incidental to the starting and stopping of said freight cars while in transit; and the object of which is to lessen the loss and damage resulting from the tearing of bags, breaking of crates, cases, etc., and consequent spilling and loss and damage of the contents thereof:

My invention also contemplates the temporary and adjustable partitioning of freight cars; and the object of which is the isolating of various consignments, commodities, grades, varieties, or brands that it may be desired to load in a freight car and retain separately and distinctly apart from each other, so that said consignments, commodities, grades, varieties, or brands can be unloaded at destination without confusion, and I attain these objects by the means illustrated in the accompanying drawings in which—

Figure 1 illustrates a front view of a movable, and detachable gate, which may also be referred to as a compression gate, a partition gate, a retaining gate, or a stabilizing gate; as it can and may perform all of these functions, but for the sake of brevity I will hereinhereafter refer to simply as a gate.

Fig. 2 illustrates a top view of a gate, and showing that the side posts are channelled.

Fig. 3 illustrates a sectional view on the line *a—a* of Fig. 1 showing two gates in position.

Fig. 4 illustrates a side view of means and method of scotching and holding automobiles in position in a freight car.

Fig. 5 illustrates a front view of a double wheel scotch.

Fig. 6 illustrates a front view of means for barring a freight car door.

Figs. 7 and 8 illustrate a front and side view respectively showing means for stowing door and gate bars when not in use.

Figs. 9 and 10 illustrate a front and side view respectively of a freight car door apron.

Fig. 11 illustrates a side view of a chain jack.

Fig. 12 illustrates a front end view of means for manipulating (or operating) a chain jack.

Fig. 13 illustrates a front view of a section of a gate post with the front side removed in order to show more clearly the mechanism therein.

Fig. 14 illustrates a top view of a channeled door bar post and detail of door bar support therein.

Fig. 15 illustrates a side view of a section of a door bar post and detail of door bar support therein.

Fig. 16 illustrates a top view of another form of door bar post.

Similar letters and numerals refer to similar parts throughout the several views.

A is a movable gate composed of two gate posts 1 and 2 (right and left), each provided with a channel 3 extending from top to lower end, and said posts are connected by a bar 4 attached to their lower ends by means of bolts passing through the front 80 and back walls of said gate posts, and said gate posts are also connected (loosely) at the tops by a bar 7, each end of which is chained to the inner edge wall of said posts, and this bar 7 is suspended by a hanger 8 from and slides on a rod 9 which is suitably connected to the frame work of the freight car; the object of these chain connections between the bar 7 and the gate posts is to prevent the gate from falling when said bar 7 is lifted (detached) out of the channels of said gate posts in order to if so desired place one or more of the other detachable bars 10 to 17 in position in said gate post channels so as to lessen the space 95 between bars, or to make a solid wall of said gate if so desired, as is shown by A' Fig. 3. To meet contingencies when walled gates are undesirable, the gate posts are provided with sliding brackets 18, 19, and 20 (*i. e.* one to support every other bar) within the channels of each of the gate posts, one of which is shown in detail in its two positions, and on a larger scale in Fig. 13, and is composed of a slotted bar 62 sliding on a pin, or bolt 105 63 extending through the walls of the gate post, and said bracket hanging normally parallel with said gate post when standing upright, and said slotted bar being provided with a right angled prong or pro-

110

jection 64 at its lower end so that when said slotted bar is lifted up until the lower end of the slot touches the pin or bolt said slotted bar can be tilted to a position at 5 right angles to the gate post channels, as is indicated by the dotted lines, and the prong or projection will be parallel and come in contact with the edge wall of the channel in the gate post and thus hold said 10 slotted bar in a right angled position relative to the gate bar post channels and form a support for a detachable bar at an intermediate point between the bottom bar 4 and the top bar 7. The prong or projection 15 formed on and at right angles to the slotted bar should only be long enough to assure the performance of its functions so as to not seriously interfere with the passage of the detachable bars downward or upward in 20 the channels in the gate posts when it is desired to assemble a solid walled gate, or to detach said bars when all or part of them are in place. 21 and 22 are tension chains (three of each are used in each end of the 25 car, *i.e.* one of 21 near each side wall of each end of the car and one in the middle, but all three at the floor line, or in other words on a line level with the tension chain holes 23 near the lower ends of the gate posts, and 30 three of 22, one of which is directly over each of the positions indicated for the three at the floor line) which engage and slide up or down on vertical anchor rods 24 (three of which are attached in some suitable 35 way to the frame work of each end of the car, and at points adapted to the requirements of the tension chains 21 and 22), and by providing chain rests 25 on the back of said anchor rods 24 at intervals and holes 40 23 at corresponding heights in the gate posts (which will also require a hole in each end of each detachable gate bar) the said tension chains will be adjustable as to height. Only one each of the tension chains 21 and 45 22 and anchor rods 24 are shown in these drawings, and then only in Figs. 3 and 4, as they are purposely left out of all the other views to obviate complexity, and to more clearly show other features.

50 If it was desirable to load a car with loose fruit or vegetables, and it was further desirable to isolate several consignments, varieties, or grades it would be necessary to estimate the space said consignment, variety, or grade would occupy, and a gate then assembled solid, *i.e.* the bars placed in the channeled posts on top of each other until the gate presented a solid wall to the desired height, and then placed in position 55 60 at the proper distance from an end of the car, the six tension chains (three of 21 and three of 22) passed through the proper tension chain holes 23 in the gate posts, and retaining pins 26, which are attached by 65 chains to the gate posts inserted in links

of the tension chains just protruding through the front face of the gate posts, and thus prevent said gate from yielding because of the pressure exerted thereon when the bin or compartment thus formed is filled, after 70 which another gate can be similarly fixed at a suitable point and another product, variety, or grade could be equally as well isolated. It is obvious that this procedure could be repeated several times in each end 75 of a freight car, and said gate could therefore be considered as either a partitioning gate, or a retaining gate.

If however the commodity to be loaded was in boxes, cases, crates, or sacks which 80 would stand up when stacked, all of a given consignment, brand, or variety could be stacked in tiers in an end of the freight car, and an assembled gate put in place against said tiers, the tension chains passed 85 through the proper tension chain holes 23 in the gate posts, and also through chain jacks B (which will be described later) when purchase pins 35, which are chained to the heads of said jacks can be inserted 90 into a link of each or any of the tension chains 21 and 22, and thereby obtain a purchase from said tension chains for said jacks to push against, and by manipulating said jacks the contents back of said gate if 95 slackly stacked will be shiftable, and if sufficient pressure is exerted by said jacks can be compressed into less space, then by inserting the retaining pins into links of the tension chains just protruding through 100 the tension chain holes 23 of the gate posts this portion of the load will be held rigidly in place, and can not therefore be damaged by toppling over or by shifting about incidental to the starting or stopping of 105 freight cars not equipped with these utilities, hence it is obvious that the gate may be considered a compression gate, a stabilizing gate, a retaining gate, or a partitioning gate.

110 It is of course obvious that a considerable weight of matter if packed in fragile crates, or boxes could not be compressed, or shifted much by pressure without crushing said crates or boxes, hence it is advisable to load a few tiers, then set a gate against them and apply the chain jacks; by repeating this operation several times, and leaving one, or more gates in position, and under tense condition in each end of the car there 115 will be little danger of damage to goods, or packages as long as the car remains upright.

To lessen the bowing tendency of the gate bars when pressure is brought to bear by 120 manipulating the jacks, or that resulting from the weight of the freight behind said gate a center post 27 is provided, which is not channeled, as it is not intended to help support the bars, but it is intended to be 125 130

used in connection with the tension chains in order to equalize the strain on the gate, and therefore prevent the bowing of the gate bars; said center post may or may not be attached to the lower bar 4, but it must not be fixed to the top bar 7.

When it is desired to unload the freight car the retaining pins 26 are taken out of the tension chain links, the tension chains 10 withdrawn from the holes in the posts, the detachable bars removed to lessen the weight of the gate, and said detachable bars stowed in rack 28 provided therefor, as illustrated by dotted lines in front and side views Figs. 15 7 and 8 respectively, and the balance of the gate then stowed near the roof of the car by swinging it into the position indicated by dotted lines in Fig. 1 where the gate posts are engaged, and supported by the 20 suspension hooks 29, the retaining pins 26 inserted into and extending through holes 30 provided for this purpose in the gate posts, and into holes provided to receive them in the suspension hooks so as to stabilize 25 said gate in this position.

Should it be desired to load automobiles for shipment in a freight car the gates would not be needed, as the double wheel scotch C illustrated in Figs. 4 and 5 is 30 better adapted for stabilizing automobiles; said double wheel scotch C consists of two concaved scotches 31 conforming in shape to an automobile wheel, supported by a bar or rod 32 supplied with tension chain holes 35 33, and carrying retaining pins 26. One of said scotches 31 may be loose and slideable on the rod 32 so as to be adjustable to automobiles of different widths, but one of them must be fixed to said rod in order to prevent 40 side slipping of the automobile by virtue of the sides of the wheels being engaged by the concavity of the scotches, one or both of which being fixed to the rod 32, and the ends of said rod contacting with 45 the sides of the freight car. If the body, or lowered top of the automobile to be loaded projected back past the rear wheels it would be necessary to scotch the automobile far enough away from the end wall of the 50 freight car to prevent said body, or lowered top from rubbing against said wall, and this can be done by passing the two side tension chains (they may of course be either 21, or 22) which are first adjusted as to 55 height through chain jacks (pipes cut to the right length would however be just as good), then through the tension chain holes 23 of a double wheel scotch rod, and the automobile then rolled into position with 60 rear wheels engaged by the scotches, the tension chains then passed through tension chain holes in another (but reversed) double wheel scotch rod, the scotches of which engage 65 the front wheels of the automobile, and then by manipulating chain jacks placed to

engage the front scotches the slack can be taken out of the tension chains, and if retaining pins are now inserted into links of said tension chains just protruding through the tension chain holes of said wheel scotch 70 rod the automobile will be held as in a vise.

As each end of a freight car can be supplied with tension chains, and scotches, it is obvious that as many automobiles can be loaded, and stabilized therein as there is 75 floor space therefor, and then as many more if the car is decked. When not in use the scotches can be stowed in the bar racks.

The chain jack consists of a tubular base 34, screw threaded for a short space on the 80 inside at one end, and at the center of the other end of said base and disposed transversely to the walls thereof is provided channels, or indentations through which a purchase pin 35 may pass to engage a link 85 of a tension chain (which is to be acted upon by said jack, and therefore is passed through said base) for a purchase on said tension chain, and also to prevent said base from turning, and a tubular core 36, screw 90 threaded throughout its length on the outside, to work inside of, and engage the threads of said base 34 (so that said core may either push or be pushed when said core or said base is turned while one is held), except that near one end of said core a square shoulder 37 is provided so that said core can be manipulated (turned) with a wrench, and said shoulder is further provided with holes in which pins may be inserted for also 95 manipulating said core, and the shouldered end of said core is rotatably connected to a head 38, to which is chained another purchase pin 35, and said head 38 is also provided with transverse channels or indentations similar to and for the same purpose as those provided in said base so that either end of said jack may be placed against the 100 object to be moved or the matter to be compressed and a purchase obtainable at the 105 other end, and so that after the jack has been manipulated and while said jack and said tension chain are in a tense (strained) condition, and therefore the matter acted upon being under compression a retaining 110 pin 26 may be inserted through the said channels in said head (or base, if said base is placed against the object moved or compressed) and engage a link of said tension chain just protruding from tension chain 115 hole 23, and thereby hold said matter in a compressed condition after jack has been 120 detached.

Fig. 6 illustrates a front view of the doorway of a freight car in which are fixed door bar posts 52 and 53 (right and left), and in which are placed a number of detachable bars 39 to 51, i. e. the bottom bar 39 and the other odd numbered bars are in place as shown in the illustration, and if the even 130

numbered bars were also in place the doorway would show solidly walled up to the top of bar 51, which would be necessary if it was desired to load the car with grain, 5 fruit, or vegetables in bulk, or at least as high as the load line, but if it was desired to load the car with freight of considerable bulk, or matter contained in large packages it would only be necessary to use the bottom 10 bar and one or two others at desired heights, and in such a case door bar post supports as shown in detail in top view Fig. 14, and sectional side view Fig. 15 are provided in the door bar posts, and are composed of a slotted rod, or bar 54 slideable up and down on a pin 55 supported by the walls of the door bar posts and hanging normally in a vertical position, and therefore parallel with the door bar posts, and if 15 desired to have a door bar supported at some intermediate position between the bottom bar 39 and the top bar 51 it would only be necessary to raise the said slotted rod or bar from its normal position the length of 20 its slot and tilt it sidewise across the channel of the door bar post to a position at right angles to said channel in said door bar post, there to rest upon a support 56 provided therefor in the channel of said 25 door bar post opposite to said pin 55, as is indicated by the dotted lines, and these provisional door bar supports are disposed at regular intervals within the channels of each of the door bar posts for the support of 30 each end of the intermediate detachable door bars.

The door bar posts 52 and 53 are adapted to being attached to the door posts, or frame work of some freight cars so as to be flush 35 with the inside walls of said cars wherein the doors thereof slide or roll on tracks which are fixed on the outside of the cars, but in others, particularly refrigerator cars the doors are hinged to the door posts 40 thereof and when closed are themselves flush with the inside walls of the car, hence door bar posts 52 and 53 are not adapted to use in such cars, and another form would therefore have to be used. Fig. 16 illustrates a top view of a door bar post 57 adapted to use in cars wherein said door bar posts would have to be attached to, and project from the inside walls of the car, and in door bar posts of this design provisional door bar supports or brackets, like those used for the support of the detachable 45 gate bars can be provided, but in either case the door bars are all detachable, and when not in use can be stowed in a rack 58 as is indicated by the dotted lines in front view Fig. 7, and side view Fig. 8.

As a further safeguard against the loss of grain which would trickle through cracks or other openings which might develop in 53 or between the door bars, a detachable apron

D which is illustrated in front view Fig. 9, and side view Fig. 10, composed of burlap or other suitable material is intended to cover the entire doorway (with all the door bars in position in said doorway), and extend several inches along the car walls on each side of the doorways as high as the top of bar 51, and to also cover several inches of the car floor extending inwardly from the doorway, and to meet this requirement 70 said apron is mounted on a rod 59 which is engaged by hooks 60 pivotally attached to each side of the doorways of the car through small openings 61 in the fabric of the apron, and as said hooks normally hang downward 80 until the ends of the apron rod come in contact with the car walls on each side of the doorway when said rod is engaged by said hooks, said apron cannot be detached from this position until the hooks 60 are lifted 85 to a position at right angles to the door posts, as is indicated by the dotted lines in Fig. 10. When not in use said apron D can be detached, rolled up on the rod 59, and stowed in the detachable bar rack. 90

By reference again to Fig. 1 it will be noted that the lower ends of the posts 1, 2, and 27 of the gate A are shown to extend below the floor line of the car, which is preferable in order to allow the tension 95 chains 21 to rest in depressions in said floor as wide and a little deeper than the diameter of said chains, so that said chains will not interfere with the level stacking of goods in the car. 100

Most of the damage done to the contents of freight cars while in transit can be attributed to the shifting of said contents on account of loose stacking, insufficient bracing, and weakness of car doors. Shifting, 105 results in crushing, and breaking and tearing of packages, *i. e.* if packages are loosely stacked they are free to move back and forth in the car when said car is suddenly started or stopped, and are crushed by impact with 110 the end walls of said car by virtue of the momentum which keeps them moving after said car has stopped suddenly, and they are of course acted upon inversely by inertia when the car is suddenly started, or if irregularly stacked, *i. e.* some stacks higher than others they would be subjected to damage by toppling over. The tearing of sacks, also incidental to shifting, results from nails left sticking in the floor and walls of the 115 car when former bracing is torn out. 120

Loose stacking or loading, and insufficient bracing after car is loaded are due to ignorance, carelessness, and in some instances to lack of proper means, all of which are 125 taken care of by the means illustrated and described herein, as the proper and efficient means for sufficient bracing and therefore stabilizing would at all times be available and convenient to use, and the need of nails 130

would be entirely eliminated in cars so equipped.

Having thus described my invention, what I claim and desire protected by Letters Patent of the United States is:

1. The combination in a freight car of chains disposed lengthwise therein and adjustably as to height anchored to each end thereof, with a multiplicity of means for partitioning freight when loaded in said car and said chains engaging said means, thus stabilizing the said means and the freight within the car.
2. The combination in a freight car of chains longitudinally disposed therein and suitably anchored thereto, with a multiplicity of various means for stabilizing and partitioning freight when loaded in said car, and suitable means for stowing said means when not in use.
3. The combination in a freight car of chains longitudinally disposed therein and adjustable as to height anchored thereto, for engaging stabilizing and partitioning gates composed of channeled outer posts and de-

tachable bars, means in said posts for supporting two or more of said bars at any desired, or intermediate height, and a bow resisting detachable center post, and said gate suspended from and sliding on a rod suitably connected to said car and near the roof thereof, and suitable means for stowing said gate near said car roof when not in use.

4. In a freight car, detachable door bars, and means for supporting one or more at various heights, grain proofing detachable aprons, and a multiplicity of stabilizing and partitioning appliances, in combination with tension chains anchored to each end and disposed lengthwise of said car to engage said stabilizing and partitioning appliances by means of retaining pins chained to said stabilizing and partitioning appliances being inserted into links of said tension chains, and suitable chain jacks for compressing freight when loaded between said stabilizing and partitioning appliances and an end of said car or when loaded between two of said stabilizing and partitioning appliances.

JOHN W. LIPPINCOTT.
